(57) **CLAIM**

The ornamental design for an automobile rear bumper, as shown and described.

DESCRIPTION

FIG. 1 is a perspective view of the exterior surface of the rear and left sides of the automobile rear bumper of the invention, the right side of the rear bumper being identical to the left side, the interior surface having no ornateness; FIG. 2 is a rear view of the exterior surface of the rear bumper illustrated in FIG. 1, the interior surface having no ornateness; and,

FIG. 3 is a side view showing the exterior surface of the right side of the rear bumper illustrated in FIG. 1, the left side of the rear bumper being identical to the right side, the interior surfaces having no ornateness.

The broken lines shown in all drawing views are for illustrative purposes only and form no part of the claimed design.
